Robert D. Budlong, deceased, late of Evanston, Ill., by
Dorothy K. Budlong, executrix, Evanston, Ill., assignor
to Zenith Radio Corporation, a corporation of Illinois

Application October 10, 1955, Serial No. 38,302

Term of patent 14 years

(Cl. D56—4)

The drawing is a perspective view of a television receiver cabinet showing the new design.

That side of the television receiver cabinet not shown in the drawing is identical to the corresponding side shown.

The back of the television receiver cabinet is unornamental.

The dominant features of the design reside in those portions shown by means of full lines in the drawing.

What is claimed is:

The ornamental design for a television receiver cabinet, substantially as shown and described.
